DESIGN FOR A GRAVE MARKER

Frances R. Taylor, Broken Bow, Nebr.

Application July 30, 1934, Serial No. 52,748

Term of patent 14 years

To all whom it may concern:

Be it known that I, FRANCES R. TAYLOR, a citizen of the United States, residing at Broken Bow, in the county of Custer, and State of Nebraska, have invented a new, original, and ornamental Design for a Grave Marker, of which the following is a specification, reference being had to the accompanying drawing, forming part thereof.

Figure 1 is a view in front elevation of a grave marker, showing my new design.

Figure 2 is a view in rear elevation thereof.

Figure 3 is a top plan view.

I claim:—

The ornamental design for a grave marker as shown.

FRANCES R. TAYLOR.
